Primary Examiner — Susan Bennett Hattan*Assistant Examiner* — Marie Fast Horse(74) *Attorney, Agent, or Firm* — Mark Catan; Potomac Law Group PLLC(57) **CLAIM**

The ornamental design for a recirculating hood, as shown and described.

DESCRIPTION

FIG. 1 is a front isometric view of the recirculating hood, showing the new design;

FIG. 2 is a front elevation view thereof;

FIG. 3 is a rear elevation view thereof;

FIG. 4 is a side elevation view thereof;

FIG. 5 is another side elevation view thereof;

FIG. 6 is a top plan view thereof; and,

FIG. 7 is a bottom plan view thereof.

The broken lines in the drawings depict parts of the recirculating hood that form no part of the claimed design.
